UNITED STATES PATENT OFFICE

2,319,288

SHOE AND METHOD OF MAKING THE SAME

Corwin W. Baker, Stoneham, Mass., assignor to
United Shoe Machinery Corporation, Flemington, N. J., a corporation of New Jersey

Application June 23, 1942, Serial No. 448,078

8 Claims. (Cl. 12—142)

This invention relates to improvements in shoes and methods of making the same.

In the manufacture of welt shoes it is customary to employ an insole having an upstanding sewing rib and usually the rib is reinforced by a strip or layer of canvas or the like which is cemented to the inner side of the rib and to the insole surface adjacent to the inner side of the rib. After the inseam has been sewn the rib, and the upper materials which have been secured to the rib by the inseam, are trimmed and left in upstanding positions and suitable filling material is employed to fill the bottom cavity bounded by the rib.

In order to simplify the operations incident to the reinforcing of the insole rib and to reduce the expense incident to such operations, the present invention involves the provision, upon the inner face of the rib and the adjacent surface of the body of the insole, of a reinforcing layer or film of hardened plastic or resinous material. In accordance with the present invention, after the inseam has been sewn and the stitches have been anchored in the resinous reinforcing layer, the latter is softened and the rib, together with the portion of the upper margin which has been secured to it, are deflected or bent inwardly and downwardly until the rib lies in a substantially flat condition upon the insole body and the softened resinous reinforcing material between the flattened rib and the insole is permitted to harden and set whereupon it serves adhesively to secure the under side of the rib to the body of the insole. The inseam stitches are thus anchored in the hardened resinous material and the rib is securely bonded, in its flat condition, to the insole and permanently held against any tendency to be erected by the pull of the inseam stitches in such a way as to relieve the tension on the upper and alter the shape of the shoe. The hardened resinous material thus serves not only to provide reinforcement for the rib and a secure anchorage for the inseam stitches but also, by positively retaining the rib in its flattened condition, to enhance the shape-holding qualities of the shoe.

The invention will be explained with reference to the accompanying drawing, in which

Fig. 1 is a perspective view of a ribbed insole of a type particularly adapted for use in the practice of the method of the present invention, the insole being shown with its ribbed face up—permost in the position it occupies when it is incorporated in a lasted shoe;

Fig. 2 is a fragmentary sectional view on an

enlarged scale taken along the line II—II of Fig. 1;

Fig. 3 is a fragmentary view of a welt shoe in process of construction, the view being partly in cross-section and partly in perspective and showing the shoe as it appears at the completion of the inseaming or weltling operation;

Fig. 4 is a fragmentary cross-sectional view of the shoe showing the operation of laying the insole rib and the lasting margin of the upper; and

Fig. 5 is a fragmentary cross-sectional view of the shoe as it appears after the outsole has been attached.

The invention has been illustrated with reference to its application to the manufacture of shoes having ribbed insoles of the type disclosed in United States Letters Patent 2,268,561, granted January 6, 1942, upon application of the present inventor although it is to be understood other types of ribbed insoles may be employed. In the drawing the insole is indicated at 10 and the rib at 12. The rib 12 comprises two lips 14 and 16 which are formed by two inside channels 18 and 20 cut in the bottom surface of the insole at a slight angle to the surface. The two lips are secured together in raised positions by means of cement, as indicated at 22, to form a unitary upstanding sewing rib and the rib is preferably formed and set by molding or otherwise so that it is transversely shaped and disposed with respect to the body of the insole as best shown in Fig. 2.

The insole 10 is reinforced by an adherent layer 24 in the form of a film or coating of synthetic resin, the film or coating being applied to the inner side of the rib 12 and to the adjacent surface of the body portion of the insole. As shown, the reinforcing layer 24 is extended inwardly a short distance beyond the inner edge of the channel 18 for use in securing to the insole body the untrimmed marginal portion of the upper which extends beyond the rib.

Advantageously, the resinous layer 24 is applied in the form of a solution which is sprayed or brushed upon the insole and allowed to dry, although other methods such as the application of molten resin may be employed. Various examples of the resinous material employed are given below.

Example I

The resinous material is Vinylite resin VYNW, a product of the Carbide and Carbon Chemicals Corporation of New York, which I understand

to be a copolymer of vinyl chloride and vinyl acetate containing about 95% vinyl chloride.

If the resin is applied as a solution, the following solution may be sprayed upon or applied with a brush to the insole to produce the result shown in Fig. 2.

	Parts by weight
Vinylite resin VYNW	7.50
Propylene oxide	79.25
Plasticizer 3 GH	3.25
Isophorone	10.00

Plasticizer 3 GH is a product of the Carbide and Carbon Chemicals Corporation, which I understand to be a diphenyl benzyl benzoate.

Example II

The resinous material is Vinylite VYNS, a product of the Carbide and Carbon Chemicals Corporation, which I understand to be a copolymer of vinyl chloride and vinyl acetate containing about 87% vinyl chloride.

A suitable solution which may be sprayed or applied with a brush is as follows:

	Parts by weight
Vinylite resin VYNS	16
Santicizer #10	8
Cellosolve	15
Acetone	61

Santicizer #10 is a product of the Monsanto Chemical Company of St. Louis, Missouri, which I understand to be o-cresyl p-toluene sulfonate.

Example III

The resinous material is Vinylite resin XYSG, a product of the Carbide and Carbon Chemicals Corporation, which I understand to be a condensation product of polyvinyl acetate and butyraldehyde.

A suitable solution which may be applied with a brush is:

	Parts by weight
Vinylite resin XYSG	14
Plasticizer 3 GH	7
Ethyl alcohol	79

In case the solution is used as a spray, the same formula may be used except that the content of XYSG resin will be only 7 parts by weight.

Example IV

The resinous material is polyvinyl alcohol. A suitable solution which may be sprayed or applied with a brush is as follows:

	Parts by weight
Polyvinyl alcohol (high viscosity)	5.0
R. H. 539	2.5
Water	92.5

Example V

The resinous material is ethyl cellulose. A suitable solution which may be sprayed or applied with a brush is as follows:

	Parts by weight
Ethyl cellulose (high viscosity)	6.0
Dow Plasticizer No. 6	9
Toluol	74.5
Ethyl alcohol	18.6

Example VI

The resin is the resin put out by the Bakelite Company of New York, N. Y., under the designation XR11617, which I understand to be equal parts of polymerized vinyl acetate and a plasticizer which consists of the reaction product of

phthalyl chloride and methyl salicylate. This resin may be melted and applied with a brush.

In the manufacture of a shoe in which an insole such as the insole 10 above described is to be incorporated, the insole is assembled together with an upper 26 (Fig. 3) upon a last 28, the upper is worked over the last and the margin of the upper is secured in overlasted position to the rib 12 of the insole as by means of staples 30. Thereafter a welt 32 is secured to the upper and to the insole rib by means of inseam stitches 34. The resinous reinforcing layer 24, which extends at 25 inwardly beyond the channel 18 is then softened and the rib 12, together with the portion of the upper which overlies it (and which, as shown, extends inwardly more or less beyond the rib), are pressed downwardly until the rib and the portion of the upper extending beyond it, lie flat against the body of the insole. As indicated at 36 in Fig. 3, the softening of the resinous reinforcing layer 24 may be accomplished by the spraying thereon of a suitable solvent for the resinous substance or the solvent may be applied by means of a brush. In the various examples of resinous material above referred to the substances are of a thermoplastic nature and accordingly the softening of the substance may be accomplished by the application of heat thereto by means, for example, of a heated hand tool such as that shown at 38 in Fig. 4, the tool being shaped at one end to enter and substantially to fill the channel between the rib and the insole body and being progressively drawn along throughout the length of the channel. After the resinous layer has been softened by the use of the tool 38 the rib and the upper may be pressed down by drawing the bottom face 40 of the tool along the margin of the upper while at the same time pressing the tool downwardly to force the rib and the upper material extending beyond the rib into intimate engagement with the insole. As a practical matter the operations of softening the resinous layer and the securing of the rib and the upper to the insole by the softened resinous material may both be accomplished at a single operation by merely pressing the rib and the upper toward the insole by means of a heated presser member such, for example, as the hand tool already described, the heat from the tool softening the resinous material while the pressure of the tool serves to flatten the rib and lay it against the insole. Advantageously also these operations may be performed by the use of a Shoe Bottom Ironing Machine such, for example, as that disclosed in United States Letters Patent No. 2,095,245, granted October 12, 1937, upon application of S. J. Finn.

The softened resinous material will quickly become dry or set and the rib, and the portion of the upper margin which extends beyond it, will be securely bonded to the insole in such a manner that it will be permanently held against any strains tending to erect the rib. Thus the upper will be retained in its tensioned condition upon the last and the shape imparted to the shoe by the lasting operation will be permanently preserved. The insole rib and the overlasted upper being retained in a flat condition upon the shoe bottom, as shown in Fig. 4, little if any filling material need be employed to provide a level bottom for the reception of the outsole 42 which is now laid in place and secured by means of cutseam stitches 44, or by means of cement, to the welt 32. Having described my invention, what I claim

as new and desire to secure by Letters Patent of the United States is:

1. That improvement in the manufacture of shoes which consists in providing the inner face of the sewing rib and the adjacent surface of the body portion of a ribbed insole with a coating of plastic material in a dry or hardened condition thereby reinforcing said rib, assembling said insole and an upper on a last, tensioning the upper over the last and securing the margin of the upper in overlasted position upon the insole, stitching the overlasted upper margin, together with a welt, to the rib of the insole, softening said coating and laying the coated rib substantially flat against the coated portion of the insole body, and allowing said coating to become hardened or set and thereby rendered effective to secure the rib permanently in its substantially flat condition to the insole.
2. That improvement in the manufacture of shoes which consists in providing the inner face of the sewing rib and the adjacent surface of the body portion of a ribbed insole with a coating of plastic material in a dry or hardened condition thereby reinforcing said rib, assembling said insole and an upper on a last, tensioning the upper over the last and securing the margin of the upper in overlasted position upon the insole, stitching the overlasted upper margin, together with a welt, to the rib of the insole, applying a heated presser member to said rib and thereby laying the rib in a flattened condition upon the insole body and softening the plastic material, and allowing the softened material to set or harden thereby permanently to secure the rib to the insole.
3. That improvement in the manufacture of shoes which comprises coating the inner side of the sewing rib and the adjacent body portion of an insole with a synthetic resin solution and allowing the solution to become dry and thereby to serve as a reinforcement for said rib, assembling the insole together with an upper on a last, tensioning the upper over the last and securing the margin of the tensioned upper in overlasted position upon the insole, securing a welt together with the upper to said rib by inseam stitches, softening said synthetic resin, bending the coated rib toward said coated body portion of the insole, and pressing said parts together while allowing said coating to become hardened or set and thus rendered effective to hold the rib against any tendency to be erected by the pull of the tensioned upper and providing a substantially level shoe bottom for the reception of an outsole.
4. That improvement in the manufacture of shoes which consists in providing the inner face of the rib and the adjacent surface of the body of a ribbed insole with a coating of plastic material in a dry or hardened condition, assembling on a last said insole and an upper having a lasting margin of sufficient width to extend beyond the upper edge of said rib, tensioning the upper over the last and securing said margin in overlasted position upon the insole, securing said margin together with a welt to said rib by inseam stitches, softening said coating and laying said rib together with that portion of the upper margin which extends beyond the rib against the
5. That improvement in the manufacture of shoes which consists in providing an insole having two inner marginal channels and two raised marginal channel lips disposed one above the other, the lips being secured together by cement to form a sewing rib, providing a film of hardened synthetic resin upon the lower or inner side of the rib and upon the adjacent surface of the body of the insole, assembling on a last said insole together with an upper having a lasting margin of sufficient width to extend beyond the free edge of said rib, tensioning the upper over the last and securing the margin of the tensioned upper in overlasted position upon the insole, securing the upper together with a welt to said rib by means of inseam stitches, softening said film of synthetic resin and pressing said rib and the extension of the upper margin downwardly against the cemented body portion of the insole, and allowing said resin to harden or set to secure the rib and the upper to the insole.
6. A shoe comprising an insole having an integral marginal lip extending inwardly from its edge portion and disposed with its outer face substantially flush with the lower face of the insole, an upper having an inturned margin overlying said lip, an adherent layer of synthetic resin between said lip and the insole body permanently securing said parts together, a welt, and inseam stitches extending through the welt, the upper and said lip and having their inner portions anchored in said layer, and an outsole secured to said welt.
7. A shoe comprising an insole having an integral marginal lip extending inwardly from its edge portion and disposed with its outer face substantially flush with the lower face of the insole, an upper having an inturned margin overlying said lip and extending inwardly beyond the inner edge of said lip, a film of hardened plastic material between said lip and the insole body and between said upper margin and said insole body inwardly of said lip, said film reinforcing said lip and securing the lip and the upper permanently to the insole body, a welt, inseam stitches extending through the welt, the upper, and the lip and having their inner portions anchored in said hardened plastic material, and an outsole secured to said welt.
8. A shoe comprising an insole having two inner channels extending obliquely to substantially the same depth into the insole material and forming two channel lips having outer surface portions substantially flush with the lower side of the insole, means securing said lips together, a film of hardened plastic material between said inner lip and the insole body securing said parts together, a welt, inseam stitches extending through the welt, the upper, and said lips and having their inner portions anchored in said plastic material, and an outsole secured to said welt.

CORWIN W. BAKER.
